WALTER E. DUNCANSON, OF NEW YORK, N. Y., ASSIGNOR TO J. G. WILSON CORP., OF NEW YORK, N. Y., A CORPORATION OF VIRGINIA

VENETIAN BLIND

Application filed March 30, 1928. Serial No. 265,855.

This invention relates to a Venetian blind and more particularly to that type of Venetian blind in which heretofore a traverse roller has been employed.

5 In this type of Venetian blind the traverse rollers have been mounted in various ways but so far as I am aware in no instance has a condensed construction of the traverse roller been employed in a casing to conceal 10 the operation of the same as is contemplated in this case. In the usual type of Venetian blind it has been customary to employ a roller cord wound upon the traverse roller. The usual practice has been to place this roller 15 cord on the traverse roller between the lifting cords, and has resulted in a lifting means extending diagonally across the face of the blind and also across the opening when the blind is up. Furthermore, it is customary to 20 employ a lifting bar which is permanently connected to the lifting cords and thru which the raising and lowering of the slats is effected.

25 The object of the present invention is to overcome these several difficulties and disadvantages and in carrying out the same this Venetian blind structure is a condensed one in which the traverse roller is mounted in a casing which encloses the same, and is adapted 30 to be secured in position on either side of a window casing or between the faces thereof. In accordance with this invention, furthermore, the cord employed for actuating the traverse roller is mounted at the end thereof 35 and preferably between one of the lifting cords and the adjacent extremity of the roller, a flange being associated with the end of the roller for maintaining the roller cord in place thereon. By this structure the actuating cord 40 is placed at one side of the blind and preferably beyond the corresponding ends of the slats so as not to hang in front of the blind or across the opening. Still furthermore, in carrying out the present invention the lifting bar 45 employed is so connected to the lifting cords as to be readily detachable therefrom, thereby permitting an easy and quick means of readjustment of the lifting bar. Venetian blinds made in accordance with this invention will 50 be hereinafter more particularly described.

In the drawings Figure 1 is an elevation and partial cross section illustrating a form of Venetian blind made in accordance with my present invention.

Fig. 2 is an enlarged section on line 2—2, 55 Fig. 1.

Fig. 3 is also an enlarged section which is taken on line 3—3, Fig. 1,

Fig. 4 is an enlarged sectional plan taken on line 4—4, Fig. 1, 60

Fig. 5 is a section on line 5—5, Fig. 4.

Fig. 6 is an elevation showing a modified structure of one end of a traverse roller,

Fig. 7 is a view similar to Fig. 1 showing another form of the invention, 65

Fig. 8 is an enlarged sectional elevation illustrating the parts associated with a traverse roller at one end thereof, and

Fig. 9 is a section on line 9—9, Fig. 8.

Referring to the drawings and particularly to Figs. 1 to 6 inclusive it will be seen that the Venetian blind made in accordance with this invention is adapted to be applied to the inner side of a window casing, the inner upright faces of which are designated respectively at 10 and 11. 70

In carrying out the invention I employ a casing 12 which is adapted to completely enclose a traverse roller 13. The casing 12 as illustrated in this form of the invention may 80 be mounted on brackets 14 and 15 or otherwise secured in position relatively to the inner faces of the window casing. At one end thereof the traverse roller 13 is mounted on a screw stem 16 suitably supported by a 85 bracket 17 or otherwise fixed at the corresponding end of the casing. At the opposite end the traverse roller is mounted on a stem or axle 18 fixed in a bracket 19 and which like the bracket 17 may be suitably secured in position in the casing. It will be understood that the traverse roller is shifted longitudinally by means of the screw stem 16 as is customary in like structures and also that the traverse roller and the stem or axle 18 may 90 be so associated as to provide for the proper shifting of the traverse roller even when the screw stem and the axle are not precisely in alignment.

Associated with the traverse roller there is 100

an actuating cord 20. One end of this cord is suitably placed adjacent one end of the roller and is wound a certain number of times around the roller and then passed through an opening 21 provided therefor in the bottom wall 22 of the casing. At this end of the traverse roller the same is preferably fitted with a flange 23 in order to maintain the actuating cord in the desired position thereon. The structure is preferably such that the actuating cord at the operable end is at the side of the blind and beyond the corresponding extremities of the slats.

As indicated in Fig. 1 the free end of this actuating cord may be secured to a hook 24 provided for this purpose in the window casing.

The Venetian blind also includes a tilting bar 25 suitably mounted in brackets 26 and 27 connected to and depending from the casing 12 or otherwise. In a customary manner the tilting bar is fitted with depending longitudinal tapes 28 and 29. These tapes are employed in sets or pairs and associated therewith in spaced positions there are cross tapes, as, for example, the longitudinal tapes 28 and 28' are fitted with cross tapes 30 for supporting the slats 31 of the blind. At the bottom or lower ends of the longitudinal tapes 28 and 29 there is the usual lifting bar 32. The cords by which the lifting bar and the slats are raised and lowered are indicated at 33 and 34. These lifting cords are similarly arranged. The lifting cord 33 at one end is suitably secured in the traverse roller 13 and passes through a hole or opening 35 in the bottom wall of the casing, through an opening provided therefor in the tilting bar 25, as indicated at 36, and through holes or openings 37 in each of the slats 31. The lower outer end of the lifting cord is then threaded through a loop 38 in a cord connector 39, the extremity of the cord being then knotted as clearly indicated in Fig. 4.

In the upper face of the lifting bar 32 there is a recess 40, lying within which there is a screw eye 41. The relationship of these parts is such that the knotted end of the lifting cord and the cord connector may be passed through the eye of the screw eye in order, as will be understood, to permit the cord connector to abut against one side of the screw eye to connect the lifting cord to the lifting bar, making the lifting bar readily connectible to and disconnectible from the lifting cord. The cord connector 39 is preferably made of a relatively short length of comparatively stout or stiff wire having the central portion thereof bent or formed in a loop 38 through which the end of the lifting cord is passed and is knotted, as aforesaid, it being understood that the length of the connector 39 is sufficient to extend beyond the oppositely disposed parts of the screw eye 41, that is, the length of the connector after the

loop has been formed therein is greater than the diameter of the eye portion of the screw eye 41. It will also be understood that the diameter of the loop 38 is appreciably smaller than the inner diameter of the eye of the screw eye 41 whereby after the end of the lifting cord has been passed through the loop 38 and knotted the connector and its loop with the knotted end of the lifting cord may be readily threaded through the screw eye 41 to detachably connect the lifting cord to the lifting bar, and obviously also the lifting bar may be readily disconnected from the lifting cord by reversing this operation. Inasmuch as the lifting cord 34 is similarly connected to the traverse roller and the lifting bar it is unnecessary to repeat the description of making these connections.

In instances where it is necessary or desirable to have the diameter of the traverse roller increased to secure greater lifting power, a shell is put on the end, as indicated at 43 in Fig. 6. This drum 43 on the traverse roller shifts its position by reason of the threaded support 16 at one end so as to accommodate the lifting cord without crossing it, and a flange 44 is secured at the end to keep the cord on the drum. In this structure the axle at the end of the roller is indicated at 45. As will be understood, the drum 43 being of greater diameter than the traverse roller makes a desirable feature to take care of instances where the blind is large and heavy.

As will be understood the tilting bar 25 may be shifted and held to any angular position by a tilting cord 46 connected thereto when operating in conjunction with suitable pulleys and brake device 47 secured to the bottom wall 22.

In one form of the invention hereinbefore described the blind is adapted to be fitted on the face of a window casing and the traverse roller is mounted in a container 12 to be secured to the face. In another form the blind may be mounted so as to extend merely between the jambs of the window casing and to be secured between the same, as illustrated in Figs. 7, 8 and 9. In these figures the end walls 48 and 49 of the casing 12 lie against the oppositely disposed inner faces of the window casing or jamb.

In this construction angle supports 17 and 19 make it possible to make a very much condensed form of Venetian blind overhead, and the container having a substantial bottom bar 22 permits a construction easily detachable in workable assembly from the supports 14 and 15 on the face of a window opening.

When secured to and operated between the jambs the operating cord 50 is secured at one end to the traverse roller and is wound a number of turns around the same, and then passes over the pulley 51 mounted on an axle 52 in the lower wall of the container and then over a pulley 53 mounted on an axle 54 also in

the lower wall of the container whereby through this right angle pull the operating cord is carried to the end of the blind and beyond the ends of the slats where it may be operated and secured to a suitable hook 55 provided therefor in the inside face of the window casing. Otherwise the construction of each part of the blind as shown in Figs. 7, 8 and 9 is specifically the same as that disclosed in the other form of the invention.

10 I claim as my invention:

1. In a Venetian blind construction, having a rotatable traverse roller lifting means secured in a box, the box arranged to detachably support on brackets fastened to the window opening, a blind in assembled formation, a tilting bar for tilting the slats, tiltably secured to the underside of the box, and means secured to the tilting bar for supporting and tilting the slats, in combination with a cord depending from the rotatable, longitudinally moving lifting mechanism in the box to a position alongside of the slats for raising and lowering the slats.
2. In a Venetian blind, an assembled structure including a casing in the form of a box, mountable and demountable from brackets fastened to a window opening, a traverse roller supported for movement within the casing, a tilting bar pivotally secured to the casing or box, and supporting with tapes, a plurality of slats therefrom, a cord for operating said tilting bar and slats from one angular position to another, supporting cords connected to the traverse roller and passing through the box and slats for raising and lowering the slats, and a traverse roller operating cord wound on one end of the traverse roller and extending downward beyond the slats, in which position the cord is operable to simultaneously move the roller on its longitudinal axis to maintain the cord in the same relative position beyond the ends of the slats.

Signed by me this 20th day of March, 1928.
45 WALTER E. DUNCANSON.
